UNITED STATES PATENT OFFICE.

OREN PERKINS, OF FAYETTE, MISSOURI.

PISTON-GRINDING MACHINE.

1,391,849.

Specification of Letters Patent. Patented Sept. 27, 1921.

Application filed October 13, 1920. Serial No. 416,613.

To all whom it may concern:

Be it known that I, OREN PERKINS, a citizen of the United States, residing at Fayette, in the county of Howard and State 5 of Missouri, have invented a new and useful Piston-Grinding Machine, of which the following is a specification.

This invention relates to devices known as grinding machines, and more particularly to 10 a grinding machine especially designed for grinding over-sized pistons.

The primary object of the invention is to provide a machine of this character which may be moved to operate on the cylinder, 15 while the cylinder is mounted on the chassis of a motor vehicle, thus eliminating the necessity of removing the cylinder block, to accomplish the grinding of the piston.

A further object of the invention is to 20 provide novel means to insure the true grinding of the piston, and insure against any angular or irregular surfaces being produced on the piston or its cylinder.

With the foregoing and other objects in 25 view which will appear as the description proceeds, the invention resides in the combination and arrangement of parts and in the details of construction hereinafter described and claimed, it being understood 30 that changes in the precise embodiment of the invention herein disclosed, may be made within the scope of what is claimed, without departing from the spirit of the invention.

Referring to the drawing:

35 Figure 1 illustrates a side elevational view of a grinding machine constructed in accordance with the present invention showing the same as applied to a cylinder block, the cylinder block being shown in section.

40 Fig. 2 illustrates a sectional detail view of the connection between the operating shaft and adjusting lever.

Fig. 3 illustrates a plan view of the device.

Referring to the drawing in detail, the 45 device includes a base 5 provided with suitable openings to receive the securing bolts 6, by means of which the device may be secured to a cylinder block to accomplish the grinding operation. Connected to the 50 base 5 is a vertical standard 7, which is provided with a right angled portion 8 formed with a suitable opening to provide a bearing for the rotating shaft 9.

This shaft 9 is relatively long, and is 55 provided with a plurality of circumferential grooves 10, the grooves being arranged in

spaced relation with each other and disposed intermediate the ends of the shaft, so that the adjusting lever 11 which operates to adjust the shaft 9, vertically, may be connected 60 to the shaft 9, at various points, to lengthen or shorten the stroke of the shaft 9.

At the upper end of the shaft 9 is an operating handle 12 which has connection with the shaft to cause the rotating thereof 65 for grinding in a piston. A piston is shown as operating in the cylinder 13, the piston being indicated by the reference character 14, and has connection with the shaft 9 through the medium of the wrist pin 15, so 70 that movement of the shaft 9 will cause a relative movement of the piston 14 to grind the same within its cylinder.

The adjusting lever 11 has a forked extremity 16, between the forks of which is 75 pivotally supported a collar 17, as by means of the bolts 18, there being provided set screws 19 extending through the collar 17 from opposite sides thereof, for providing the connection between the adjusting lever 80 11 and the shaft 9, the set screws 19 being however disposed within the grooves 10 so that the connection between the lever 11 and shaft 9 will not restrict rotary movement of the shaft 9.

Pivotaly supported on the base 5, is a supporting arm 20 which has its upper extremity disposed between the forks of the adjusting lever 11 at a point substantially intermediate the ends thereof, the connection 90 between the arm 20 and lever 11 being made through the pivot pin 21. Thus it will be seen that by rocking the lever 11, the shaft 9 may be moved or reciprocated vertically to cause a corresponding movement of the piston 14 within its cylinder.

Upon rotation of the shaft 9, rotary movement is imparted to the piston 14 to accomplish the grinding of the same, it being understood however that in the operation of 100 the device, the lever 11 is operated simultaneously with the shaft 9, to cause the piston 14 to take a combined rotary and reciprocating movement to insure the true grinding thereof.

It might be further stated that if it is desired to advance piston 14 a greater distance within the cylinder under operation, the set screws 19 may be removed, from the groove as shown by Fig. 1 of the drawing, 110 and positioned in one of the upper grooves.

It is to be understood that in the use of

the grinding machine, a suitable grinding medium such as powder or paste is to be employed to resurface the cylinder.

Having thus described the invention, what is claimed as new is:

In a grinding machine, a base, a standard having connection with the base, said standard having a right angled upper extremity, said right angled upper extremity 10 having an opening providing a bearing, a rotatable shaft supported within the bearing, said shaft having a plurality of circumferential grooves disposed in spaced relation with each other, an adjusting lever, 15 a collar having pivotal connection with the

adjusting lever, set screws extending through the collar and having their ends disposed within a predetermined groove of a shaft to connect the adjusting lever and shaft, means for connecting a piston to one end of the shaft, and means for rotating the shaft. 20

In testimony that I claim the foregoing as my own, I have hereto affixed my signature in the presence of two witnesses.

OREN PERKINS,

Witnesses:
